THERMOSTAT

Original Filed Nov. 17, 1931

UNITED STATES PATENT OFFICE

2,004,667

THERMOSTAT

Robert Henri Mautsch, Brussels, Belgium, assignor to The Westinghouse Air Brake Company, Wilmerding, Pa., a corporation of Pennsylvania

Original application November 17, 1931, Serial No. 575,512. Divided and this application March 28, 1933, Serial No. 663,149. In Great Britain November 18, 1930

5 Claims. (Cl. 297—11)

This invention relates to steam heating apparatus for railway vehicles and other purposes of the kind in which the radiator of the apparatus is provided with a thermostatically operated regulating mechanism, comprising a regulating rod or tube, for automatically controlling the supply of steam to the radiator, the present application being a division of my application, Serial No. 575,512, filed November 17, 1931.

- 10 According to the principal feature of the invention, the regulating rod or tube is composed of two or more parts welded or otherwise secured to one another, these parts having different temperature coefficients of expansion and by providing parts of different lengths which when secured end to end as above described constitute the full length of the regulating element, it will be evident that the temperature coefficient of the rod or tube as a whole can have any desired value.
- 15 Furthermore, the regulating rod or tube may be tubular and perforated wholly or in part so as to reduce the mass thereof and also to permit access of steam to the interior of the element, thus rendering the regulating action still more prompt and efficient. For example, the regulating rod or tube may comprise an intermediate perforated tubular portion of copper interposed between and secured to two rods of the alloy known under the registered trade name "Invar".
- 20 In the accompanying drawing, Fig. 1 is a view of a regulating element for the thermostatic control of a radiator and embodying one form of my invention; Fig. 2 a view of a regulating element embodying another form of my invention; and
- 25 Fig. 3 a view of another modification.

According to one form of my invention, as shown in Fig. 1, a valve element 7 is formed integral with or rigidly secured to a regulating rod or tube which may be composed of two or more parts welded or otherwise secured to one another, these parts having different relatively low temperature coefficients of expansion and by providing parts of different lengths which when secured end to end as above described constitute the full length of the regulating rod or tube, it will be evident that the temperature coefficient of the regulating rod or tube as a whole can have any desired value.

30 As shown in Fig. 1, the rod may be formed of two parts 1 and 2 composed of a special alloy known as "Invar" having one coefficient of expansion and one part 3 composed of copper, a valve element 7 being secured to one end of the rod.

According to the construction shown in Fig. 2, the rod may be formed of sections 4 and 5 composed of "Invar" and an intermediate section 6 composed of copper. The section 6 is in the form of a tube formed from a sheet of metal having spaced perforations 8, the edges of the sheet parallel to the axis of the tube being butted, but not welded or otherwise joined.

When a perforated tube is used, the mass of the rod is reduced, and the perforations permit access to the interior of the tube, of steam, so as to render the regulating action more prompt and efficient.

The regulating rod may also be formed as shown in Fig. 3, of three tubular sections 9, 10 and 11, the sections 9 and 11 being composed of copper and the section 10 of steel, preferably stainless steel.

Other metals having different coefficients of expansion may be employed, the principle being that the temperature coefficient of expansion for the rod or tube as a whole can be made of the exact desired value by properly proportioning the lengths of the sections having different coefficients of expansion.

While one illustrative embodiment of the invention has been described in detail, it is not my intention to limit its scope to that embodiment or otherwise than by the terms of the appended claims.

Having now described my invention, what I claim as new and desire to secure by Letters Patent, is:

1. A heat expansible element for a thermostat comprising integrally united longitudinal sections of heat expansible and non-heat expansible material forming a uniform lineal structure of definite length, the heat expansible section being a perforated tube, and the length of the expansible section being so proportioned with respect to the length of the non-expansible sections that the element as a whole has any desired predetermined coefficient of expansion.

2. A heat expansible element for a thermostat comprising two non-heat expansible sections and an integrally united heat expansible section intermediate the non-expansible sections forming a uniform lineal structure of a definite length, the length of the expansible section relative to the lengths of the non-expansible sections being chosen such that the coefficient of expansion of the element as a whole is a selected predetermined quantity.

3. The method of making heat expansible elements of uniform length for thermostats having

5 predetermined selected coefficients of expansion which consists in uniting sections of heat expansive material and non-heat expansive material of varying lengths to form a uniform lineal structure of definite length, the lengths of the sections being so proportioned as to provide an element having any desired coefficient of expansion.

10 4. The method of making heat expansive elements of uniform length, for thermostats having predetermined selected coefficients of expansion, which consists in uniting sections of heat expansive material and non-heat expansi-

ble material of varying lengths proportioned to provide a uniform lineal structure of definite length having the desired coefficient of expansion.

5 5. The method of making heat expansive elements of definite length, for thermostats having selected predetermined coefficients of expansion, which consists in uniting a heat expansive section intermediate two non-expansive sections to form a uniform integral linear structure, the relative lengths of the several sections being 10 chosen to provide the desired coefficient of expansion of the element as a whole.

ROBERT HENRI MAUTSCH.
